**APPARATUS FOR STRINGING AND TENSIONING
PLURAL STRANDS OF FENCE WIRE**
Sherwood S. De Forest, Coraopolis, Pa., assignor to
United States Steel Corporation, a corporation of New
JerseyFiled Feb. 8, 1961, Ser. No. 87,833
12 Claims. (Cl. 242—86.7)

This invention relates to wire fence of the type that is formed of plural strands of fence wire strung along a line of fence posts. As indicated, it relates more particularly to an apparatus for simultaneously stringing plural strands of fence wire under the tension required for fastening to the fence posts.

The apparatus of this invention, more specifically, comprises a plurality of dispensing reels for coils of fence wire, such as barbed wire and the like, from which the strands are dispensed in being strung along a line of fence posts, and a tensioning mechanism that operates to resist the dispensing movement of the strands from said reels and thus place them under tension. The fence wire dispensing reels are mounted on a tractor-drawn carriage in such manner that the strands of wire are pulled therefrom as the carriage is drawn forwardly along a line of fence posts. The tensioning mechanism, in a manner to be described, comprises a frictional braking unit also mounted on the carriage that includes a plurality of tensioning discs, which through separate mechanical drives are rotated at speeds corresponding to the rates at which the fence wire strands are being strung and which have their rotation subject to a retarding torque that is applied by frictional brake elements. The tensioning discs thus place each of the fence wire strands being strung under a tension that is determined by the frictional braking torque resisting their rotation. Since the tensioning mechanism places each of the strands under equal tension, the vertical spacing between adjacent strands is maintained uniform and the strands are thus strung in parallel positions.

Other objects and advantages of the invention will become apparent from the following description and accompanying drawings, in which:

FIGURE 1 is a diagrammatic plan view of the fence erecting machine to which the apparatus of this invention relates and forms a part thereof;

FIGURE 2 is an enlarged plan view of the machine shown in FIGURE 1;

FIGURE 3 is an elevational view looking from the right of FIGURE 1;

FIGURE 4 is an enlarged elevational view taken in a direction looking from the left of FIGURE 2 which shows the plural wire strand stringing and tensioning apparatus of this invention;

FIGURE 5 is an end elevational view of a portion of the apparatus shown in FIGURE 4 taken in a direction looking from the right thereof;

FIGURE 6 is an enlarged elevational view of one of the fence wire strand dispensing reels of this invention;

FIGURE 7 is an elevational view of the braking unit shown in FIGURE 1 which illustrates the manner in which it is mounted on a supporting frame therefor; and

FIGURE 8 is an exploded view showing the parts of the braking unit shown in FIGURE 7, in which portions of such parts are broken away and shown in section.

The apparatus of this invention forms part of a fence building machine that has as its principal purpose the reduction of manual labor required for erecting farm and highway fencing. Such machine, as diagrammatically shown in FIGURE 1, comprises a carriage 1 that is pulled forwardly along a line of fence posts 2 by a tractor 3, the carriage being connected with the tractor by a conventional three-point hitch in a manner to be described. A

2

vertical reel 4 for dispensing woven wire fencing from a coil thereon and a tensioning clamp 5, which form the subject matter of copending application Serial No. 83,706, filed January 19, 1961, and to which reference is made for a more detailed explanation and showing thereof, are mounted on the carriage 1 together with the dispensing mechanism 6 of this invention. In operation, the dispensing mechanism 6 and vertical reel 4 operate to string fence wire, designated diagrammatically by the broken line 7, along the line of fence posts 2 as the carriage 1 is pulled forwardly by the tractor 3. After being placed under tension, the wire 7 is fastened to the fence posts 2. A fence post driver 8, the mounting of which forms the subject matter of copending application Serial No. 86,422, filed February 1, 1961, at the forward end of the carriage 1 is operated to install fence posts 2 at spaced intervals along the fence line. As indicated, this invention is directed to the mechanism 6, which in a manner to be described operates to string plural strands of fence wire under tension along the fence posts 2.

As shown in FIGURE 2 of the drawings, the carriage 1 comprises a pair of laterally spaced platforms 9 and 10 that have pivotal connections 11 at their forward ends to a draft bar 12. The connection of the draft bar 12 with the tractor 3 comprises a conventional three-point tractor hitch which includes a pair of lift links 13 and a stabilizing link 14 (FIGURE 3). The lift links 13 are pivotally connected to lugs 15 on the draft bar 12, and the stabilizing link 14 has a pivotal connection 16 to the upper end of a frame 17 that is mounted on the draft bar 12. When attached to a tractor, the links 13 and 14 furnish a support for the forward end of the carriage 1 which is supported at its other end for rolling movement over the ground by casters 18 at the trailing ends of each of the platforms 9 and 10. When disconnected from the tractor, the forward end of the carriage 1 is supported by detachable casters 19 which have upwardly extending stems 20 that are removably secured in brackets 21 secured to the draft bar 12.

The fence post driver 8 has a central location on the draft bar 12 and is arranged in the space 22 between the platforms 9 and 10. The platform 9 furnishes a support for both the vertical reel 4 and the tensioning clamp 5 mentioned above, and the dispensing mechanism 6 of this invention, which comprises a plurality of horizontal reels 24 that are adapted to dispense plural strands of fence wire, such as barbed wire, from coils supported thereon. The fence wire 7, with reference to FIGURE 1, is attached to one of the fence posts 2 and is dispensed from the reels 4 or 24 upon forward movement of the carriage 1 along a line of fence posts by the tractor 3. As described in the above mentioned copending application Serial No. 83,706, woven fence wire 7 being dispensed from the vertical reel 4 travels through a vertical pass between tensioning clamping elements 25 and 26 that form part of the tensioning clamp 5 and are operated into clamping engagement with the fence wire 7 so that subsequent forward movement of carriage 1 will operate to apply tension to the wire 7 prior to its being fastened to the posts 2 along which it has been strung. The horizontal reels 24 in accordance with the present invention are provided with chain and sprocket drives to a tensioning unit 27 that operates to apply tension to plural strands of fence wire being dispensed from the reels 24 independently of the tensioning clamp 6.

The platform 10 in operation furnishes a support for carrying a plurality of fence posts and, for this purpose, has vertically extending members 28 and 29 at opposite ends thereof between which the ends of the fence posts 2 are received to hold them in position on the platform 10. In addition, the platform 10 furnishes a stand for a workman operating the machine.

Since the fence post driver 8 is conventional, it will be sufficient to indicate that it includes a fence post driving element 30 that is mounted for guided vertical movement in a guide housing 31 carried by the frame 17. Upon release from the position shown in FIGURE 3, the element 30 gravitates downwardly to drive a post positioned therebelow into the ground and is thereafter returned to its elevated position for another post driving operation by a mechanical drive 32 operated from a conventional tractor power take-off (not shown). After driving each fence post in this manner, the carriage 1 is moved forwardly to the position at which the next fence post 2 is to be driven. The central location of the post driver 8 on the draft bar 12 and the space 22 between the platforms 9 and 10 provide for free forward movement of the carriage 4 to the next fence post driving position after each operation of the driver 7 to install a fence post. As described in application Serial No. 86,422, mentioned above, the mounting of the post driver housing 31 on the frame 17 includes a bearing 33 that provides for its rotation about an axis extending transversely of the draft bar 12, trunnions 34 that provide for its tilting movement about an axis parallel to the draft bar 12, and a slide support for the frame 17 on the draft bar 12 so that the position of the driver 8 may be adjusted laterally in the space 22 between the draft links 13. Separate double-acting reversible fluid-pressure motors 35 and 36 operate respectively to tilt the driver housing 31 about the axes of the bearing 33 and the trunnions 34, and a bell-crank linkage 37 operated by a pivoted hand-lever 38 shifts the frame 17 and thereby the housing 31 laterally on the draft bar 12.

As best shown in FIGURES 4 and 5, a rectangular frame 40 furnishes a support for the reels 24 and the frictional tensioning unit 27 of this invention on the platform 9. The frame 40 is comprised of spaced side bars 41, a top bar 42, and a center bar 43 extending between and bracing the side bars 41 at points between their upper and lower ends. The lower ends of the side bars 41 have outwardly turned base members 44 that are welded to the platform 9. The reels 24, preferably four in number as shown in FIGURE 4, are mounted in vertically spaced pairs on the side bars 41 in symmetrically and circumferentially spaced positions about the axis of the tensioning unit 27, which is supported on the frame center bar 43 at a point centrally thereon. The reels 24 and unit 27 respectively rotate about horizontal axes that are parallel and extend in a direction transversely of the path of movement of the carriage along a fence line. Each of the reels 24 in operation is adapted to support a coil of fence wire from which the strands of wire being strung along a fence line are dispensed during forward movement of the platform 9 by the tractor 3. For a purpose to be described such coils of fence wire are mounted on the reels 24 so that adjacent pairs about the axis of the braking unit 27 rotate in opposite directions as indicated by the arrows in response to the strands of fence wire being pulled therefrom.

The strands of wire being dispensed are directed upwardly from each reel 24 over guide sheaves 45 supported on the frame 40, the strands being dispensed from the upper pair of reels 24 being respectively guided over the pair of guide sheaves supported on the top bar 42 of the frame 40 and the strands being dispensed from the lower pair of reels 24 being respectively guided over the sheaves 45 mounted on the side bars 41. From the sheaves 45, the strands of wire are guided over four vertically spaced sheaves 46 that are mounted in vertically spaced positions on a frame member 47 carried by the platform 9 for rotation about a common vertical axis. From the sheaves 46, the strands of wire travel over vertically spaced guide sheaves 48 (FIGURE 3) that are supported for rotation about vertically spaced horizontal axes on a supporting bar 49. The bar 49 has a plurality of vertically spaced openings 50 therein in which the guide sheaves 48 are mounted and which provide for adjustment of their relative vertical positions. The sheaves 46 and 48 in oper-

ation support the strands of fence wire in vertically spaced positions and guide the stringing movement of such strands along parallel paths in a common vertical plane. From the sheaves 48, the strands of fence wire extend rearwardly as indicated by the broken line 7 in FIGURE 1 to a position where they are anchored to the fence posts 2 so that forward movement of the carriage 1 by the tractor 3 will result in the strands being pulled from coils of fence wire on the reels 24 as the carriage 1 is moved along the line of fence posts.

Each of the reels 24 has an identical construction and mounting on one of the side bars 41 as best shown in FIGURE 6. With reference to FIGURE 6, each reel 24 comprises a pair of end members 52 and 53 and a stem 54 extending axially therebetween on which a coil of fence wire is supported. The stem 54 comprises a hollow pipe 55 that is secured centrally of the end member 52 and extends outwardly therefrom and a plurality of coil supporting bars 56 secured to the end member 52 in axially extending and circumferentially spaced positions about the pipe 55. The end member 53 is a plate that is detachably connected to the outer end of the pipe 55 by a bolt 57 and has a circular disc 58 secured to the inner surface thereof for holding the outer ends of the bars 56 against flexing movement toward the pipe 57. A mounting shaft 59 has one end rigidly secured in the pipe 55 and its other end rotatably supported in a bearing 60 that is secured by a mounting plate 61 to the side bar 41. In operation, the stem 54 and end members 52 and 53 of each reel 24 rotate in response to a strand of wire being withdrawn from a coil supported on the stem 54 and the shaft 59 turns in the bearing housing 60. A sprocket wheel 62 is secured to each end member 52 by a hollow tubular connecting member 63 for rotation therewith. While each reel 24 has an identical construction, the tubular connecting members 63 have different axial lengths so that the sprocket wheels 62 on the different reels 24 are spaced axially relative to each other as shown in FIGURE 5 for a purpose to be described.

The tensioning unit 27, as best shown in FIGURES 7 and 8, comprises four sprocket wheels 65 that are rotatably supported by bearings 66 in axially spaced positions for rotation on a shaft 67, there being a separate sprocket wheel 65 for each of the dispensing reel sprocket wheels 62 for a purpose to be described. Each of the sprocket wheels 65 has a braking surface 68 on one side thereof and a frictional brake lining 69 on the other side thereon. The brake linings 69 are annular discs of brake lining material that have a cemented connection 70 to an annular disc 71 of Masonite or similar mounting material, which in turn has a cemented connection 72 to the sprocket wheel 65. The sprocket wheels 65 are arranged on the shaft 67 in axially spaced positions between a pair of frictional braking elements 73 and 74. The braking element 73 is a steel disc through which the shaft 67 extends and has a welded connection with the frame center bar 43 by which it is held against rotation. The disc 73 provides a braking surface 75 that has frictional engagement with the surface 76 of the brake lining 69 on the adjacent sprocket wheel 65. The braking element 74 is a steel disc that has a welded connection 77 with a bolt 78 on one end of the shaft 67 which holds it against rotation relative to the shaft 67. The inner-face of the disc 74 has a lining 79 of braking material that engages the surface 68 on the outermost or adjacent sprocket wheel 65. The brake lining 79 is a disc of brake lining material that has a cemented connection 80 to a disc 81 of Masonite or other mounting material, which in turn has a cemented connection 82 to the steel disc 74. The other end of the shaft 67 extends through aligned openings 83 in the braking element 73 and a pair of mounting lugs 84 and 85 that are welded to the frame center bar 43 in positions depending therefrom, the braking element 73 having a welded connection 86 with the mounting lug 84. A bolt 87 (FIGURE 7) detachably received in an opening

88 extending diametrically of the shaft 67 engages a block 89 that is welded in position between the lugs 84 to hold the shaft 67 against rotation, but permits axial movement of the shaft 67 in the openings 83. A spring 90 mounted concentrically on the outer end of the shaft 67 has one end bearing against the mounting lug 85 and its other end bearing against a nut 91 threaded on the outer end of the shaft 67 as shown in FIGURE 7. The spring 90 provides a bias for moving the shaft 67 and the end disc 74 thereon in a direction toward the braking element 73 to maintain the braking sprocket wheels 65 engaged with each other and with the end discs 73 and 74 as shown in FIGURE 7. The biasing action of the spring 90 may be adjusted by rotating the nut 91 and a handle 92 is welded to the nut 91 to facilitate this adjustment.

It will be recalled that each of the tubular connecting members 63 on the reels 24 have different axial lengths so that the sprocket wheels 62 that rotate with the reels 24 are axially spaced relative to each other as best shown in FIGURE 5. The axial spacing of the sprocket wheels 62 in this respect corresponds to the axial spacing of the sprocket wheels 65 of the braking unit 27 so that each reel sprocket wheel 62 lies in a vertical plane containing one of the braking unit sprocket wheels 65. Sprocket chains 93 are trained over the sprocket wheels 62 and 65 that lie in a common vertical plane and form a drive connection between each reel 24 and one of the braking unit sprocket wheels 65. As the result of the driving connection provided by the sprocket chains 93, rotation of each reel 24 in response to a strand of wire being pulled from a coil of wire supported thereby imparts rotation to one of the braking unit sprocket wheels 65. Since the reels 24 rotate in opposite rotational directions as explained above, adjacent sprocket wheels 65 rotate in opposite rotational directions on the shaft 67. This rotation of the sprocket wheels 65 is subject to a retarding torque that is developed by the brake lining surfaces on opposite sides of each sprocket wheel 65. This retarding torque is applied through the chains 93 to the reel sprocket wheels 62 which thus retard the rotation of the reels 24 and apply tension to each of the strands of wire being pulled therefrom.

From the foregoing it will be apparent that the apparatus of this invention operates to string plural strands of fence wire under equal tension along a line of fence posts. Attention is particularly directed to the fact that the coils of fence wire are placed on the reels 24 so that adjacent pairs thereof as well as adjacent ones of the tensioning unit braking discs or sprocket wheels 65 will rotate in opposite rotational directions in response to the 50 strands of wire being pulled therefrom during a stringing operation of the apparatus. After placing the coils of fence wire on the reels 24 in this manner, the strands of fence wire are strung over the guide sheaves 45, 46 and 48 and fastened to one of the fence posts 2 as described above so that the strands will be dispensed from the reels 24 when the carriage 1 is pulled by the tractor 3 along the line of fence posts 2. By reason of the retarding torque developed by the tensioning unit 27 of this invention, the strands of fence wire are strung under equal tension, which may be regulated by rotating the nut 91 to adjust the biasing action of the spring 90 and thereby the frictional braking action of the brake linings 69 and 79, and thus in parallel positions equally spaced relative to each other along the line of fence posts 2.

While one embodiment of my invention has been shown and described it will be apparent that other adaptations and modifications may be made without departing from the scope of the following claims.

I claim:

1. Apparatus for stringing plural strands of fence wire under tension along a line of fence posts comprising the combination with a platform movable along said fence line, and a plurality of rotatable fence wire dispensing reels mounted on said platform, there being one of said

reels for each of said strands and each being adapted to support a coil of fence wire from which one of said strands is dispensed when said platform is moved along said fence line, of a common braking unit comprising a plurality of rotatable members mounted in axially spaced positions for rotation about a common axis, there being one of said members for each of said strands, a plurality of separate means for rotating said rotatable members respectively in response to dispensing movement of said strands, and frictional braking means for resisting the rotation of each of said rotatable members and operating through said responsive means for applying tension to each of said wire strands.

2. Apparatus as defined in claim 1 characterized by 15 said separate means operating to rotate adjacent ones of said rotatable members in opposite rotational directions.

3. Apparatus as defined in claim 1 characterized by each of said separate means comprising a chain-belt and 20 sprocket drive forming a driving connection between one of said reels and one of said rotatable members.

4. Apparatus as defined in claim 1 characterized by 25 said reels being rotatable about parallel axes respectively disposed in circumferentially spaced positions about said common axis.

5. Apparatus for stringing plural strands of fence wire under tension along a line of fence posts comprising the combination with a platform movable along said fence line, and a plurality of rotatable fence wire dispensing 30 reels mounted on said platform, there being one of said reels for each of said strands and each being adapted to support a coil of fence wire from which one of said strands is dispensed when said platform is moved along said fence line, of a mechanism for placing each of the 35 strands being strung under equal tension comprising driving sprocket wheels secured to said reels for rotation therewith in response to dispensing movement of said fence wire strands therefrom, a plurality of driven sprocket wheels mounted in axially spaced positions for 40 rotation about a common axis, chain belts forming driving connections between said driving sprocket wheels and driven sprocket wheels, and frictional braking means for retarding the rotation of said driven sprocket wheels to thereby apply a retarding torque to said reels and a 45 corresponding tension to said strands.

6. Apparatus as defined in claim 5 characterized by the provision of a single means for adjusting the retarding action of said frictional braking means on each of said driven sprocket wheels.

7. In apparatus for stringing plural strands of fence-wire along a line of fence posts, a platform for movement along said fence line, a frame mounted on said platform, a supporting shaft mounted for endwise movement on said frame, a first frictional braking disc secured to said frame and having an opening therein through which said shaft extends, a second frictional braking disc secured to said shaft in a position spaced from said first braking disc, a plurality of frictional braking discs corresponding in number to the number of said 55 strands and mounted for independent rotation on said shaft in axially spaced positions between said first and second braking discs, means resiliently biasing the endwise movement of said shaft on said frame in a direction for moving said second disc toward said first disc to 60 maintain adjacent ones of said plural discs in frictional engagement with each other and the end ones of said plural discs in frictional engagement respectively with said first and second discs, a plurality of rotatable fence wire dispensing reels mounted on said platform, there 65 being one of said reels for each of said strands and each being adapted to support a coil of fence wire from which one of said strands is dispensed when said platform is moved along said fence line, and means for applying a 70 retarding torque to rotation of said reels in response to dispensing movement or said strands comprising chain

and sprocket drives respectively forming a driving connection between each of said reels and one of said plurality of braking discs.

8. An apparatus as defined in claim 7 characterized by the provision of means for adjusting the biasing action of said resilient biasing means on said shaft to thereby adjust the retarding torque applied to said reels and the tension on said strands.

9. In apparatus for stringing plural strands of fence wire along a line of fence posts, a supporting frame, a shaft mounted for endwise movement on said frame, a first frictional braking disc secured to said frame and having an opening therein through which said shaft extends, a second frictional braking disc secured to said shaft in a position spaced from said first braking disc, a plurality of frictional braking discs corresponding in number to the number of said strands and mounted for independent rotation on said shaft in axially spaced positions between said first and second braking discs, means resiliently biasing the endwise movement of said shaft on said frame in a direction for moving said second disc toward said first disc to maintain adjacent ones of said plural discs in frictional engagement with each other and the end ones of said plural discs in frictional engagement respectively with said first and second discs, a plurality of reels for supporting coils of fence wire from which said strands of fence wire are dispensed in being strung along said fence line, and separate means for rotating said frictional discs respectively in response to dispensing movement of said strands from said reels.

10. An apparatus as defined in claim 9 characterized by said last named means operating to rotate adjacent ones of said plurality of friction discs in opposite rotational directions.

11. An apparatus as defined in claim 9 characterized by said reels being symmetrically disposed in circumferentially spaced positions about said shaft.

12. Apparatus for stringing plural strands of fence wire under tension along a line of fence posts comprising the combination with a platform movable along said fence line, and a plurality of rotatable fence wire dispensing reels mounted on said platform, there being one of said reels for each of said strands and each being adapted to support a coil of fence wire from which one of said strands is dispensed when said platform is moved along said fence line, of a common braking unit comprised of a plurality of separate means respectively responsive to the dispensing operation of said strands for placing said strands under equal tension, each of the said separate means of said braking unit comprising a rotatable member that is rotated in response to dispensing operation of one of said strands and a frictional brake for retarding its rotation so that it operates to resist the dispensing operation of said one strand and to thereby place it under tension.
